CLAIM

The ornamental design for a ladder rack for a cooking cavity as shown and described.

DESCRIPTION

FIG. 1 is a side perspective view of a ladder rack for a cooking cavity shown in an environment of use in accordance with our new design;

FIG. 2 is a side perspective view of the ladder rack for a cooking cavity;

FIG. 3 is a left side elevation view thereof;

FIG. 4 is a top plan view thereof;

FIG. 5 is a front elevation view thereof; and,

FIG. 6 is a cross-section view of the ladder rack for a cooking cavity taken along line VI-VI shown in FIG. 5.

In FIG. 1, the oven shown in broken lines is environment that forms no part of the claimed design. In FIGS. 1-6 the evenly spaced broken lines show portions of the article and form no part of the claimed design. The dash-dot broken lines define the bounds of the claimed design and form no part thereof.
